CLAIM

The ornamental design for a hinge for a utility vehicle door, as shown and described.

DESCRIPTION

FIG. 1 is an isometric view of a hinge for a utility vehicle door showing my new design, the hinge for a utility vehicle door being shown in a closed position;

FIG. 2 is another isometric view thereof shown from a different angle;

FIG. 3 is front elevation view thereof;

FIG. 4 is rear elevation view thereof;

FIG. 5 is a top plan view thereof;

FIG. 6 is bottom plan view thereof;

FIG. 7 is right elevation view thereof;

FIG. 8 is left elevation view thereof;

FIG. 9 is a front elevation with the hinge for a utility vehicle door being shown in the open position; and,

FIG. 10 is a rear elevation with the hinge for a utility vehicle door being shown in the open position.

1 Claim, 10 Drawing Sheets
